SHOE-END LASTING MACHINE

Wilhelm Müller, Weissenfels-on-the-Saale, Germany, assignor to the firm of Nollesche Werke Kom. Ges., Weissenfels-on-the-Saale, Germany

Application May 27, 1933, Serial No. 673,154
In Germany June 6, 1932

9 Claims. (Cl. 12—4)

The present invention relates to machines for lasting the toe and heel part of shoes by means which are partly or wholly driven by a hydraulic medium. The working instrumentalities of the 5 machine are carried by plungers the cylinders of which are according to the invention in constant communication with the pressure outlet of a continuously working pump. The pressure fluid is continuously fed through the cylinders, 10 and a valve under the control of the operator directs it either on the pressure side of the plungers to act upon the work or on the opposite side of the plungers so as to bring the latter into position of rest allowing a continued free 15 and idle circulation of the fluid. Thus by means of a treadle the machine can be set in motion and operated as if it were driven by a transmission belt or by an electric motor.

Lasting machines which automatically last 20 the heel part or the toe part of shoes are known. These machines are mostly built separately for lasting the heel or for lasting the toe and have the disadvantage that for several reasons different adjustments or arrangements of the nailing 25 and wiping means are necessary for lasting pointed ladies' shoes and for lasting of large gentlemen's shoes. These adjustments and rearrangements of the machines diminish the output of the machines. Moreover it is practically 30 not feasible to provide separate wipers for all different shoe forms in order to last accurately every single shoe.

The present invention shows and describes a 35 lasting machine adapted to automatically and successively last the heel part or the toe part of any form of shoes without the exchange of parts and without the adjustment of the nailing wipers. This is obtained by the hydraulic operation 40 of the wipers. The tack driving means are fastened to the wipers and adapt themselves to the given shoe form.

These and other features of the invention are 45 described in the following specification and are illustrated in the attached drawings, in which

Fig. 1 shows a vertical section along the line I—I of Fig. 4, the plungers being in working position.

Fig. 2 is a like section, the plungers being 50 shown in position of rest.

Fig. 3 shows the section along the line III—III of Fig. 1 through the middle of the shoe supporting device.

Fig. 4 is a front view of the machine.

Fig. 5 shows the position of the wipers and

of the tacking devices when lasting the shoe-toe.

Fig. 6 is a section on the line VI—VI of Fig. 5 through the rear wiper.

Fig. 7 is a section on the line VII—VII of Fig. 5 through the front wiper.

Fig. 8 is a plan view of the wipers when lasting the shoe-heel, and in part a horizontal section showing the arrangement of the plungers.

The shoe to be lasted is placed upon the last 10 pin 1. The toe end of the shoe repose upon the toe support 2 which is adjustable vertically by the serrated nut 3. The toe support is adjustable lengthwise for different sizes of shoes in the groove 4 of the table 5. The table 5 is guided in 15 a curved groove 5' of the frame 6 and can be clamped by the lever 7 so that the toe part or the heel part of the shoe is held in a horizontal position. The frame 6 slides in the guide 8 fastened to the plunger 9. On the frame 6 is mounted a 20 two-part loose ring 10 connected by the bolt 12 to the plunger 11 adapted to pull the frame inward. The whole device for holding the shoe can be lowered against the pressure of the spring 15 by the handle 13 engaging with a sliding block into 25 the groove of the plunger 9.

The continuously working pump 16 is screwed to the machine frame 17 which forms a fluid reservoir. It sucks the pressure fluid (thin pressure oil) and presses it through the overflow 30 valve 18 into the upper leads 20 and 21.

As shown in Fig. 1 the shoe to be lasted is held by hand against the fixed abutment 22. Its vertical position is determined by the sole presser 23 against which the shoe is held by the pressure 35 spring 15. The sole presser 23 is vertically adjustable. To this end its front face forms a rack engaging into the toothed shaft 24. On the shaft 24 is fastened a ratchet wheel held in position by a pawl 25 pivoted on the frame 26. 40

In the body 27 there are arranged several radial pressure plungers 28, 28', 28'', . . . all of which communicate with a single rear pressure chamber 29 built in the form of a semi-circle. The plungers 28, 28', 28'', . . . are connected by shackles 30 45 to the carriers 31 of the nailing devices and to wipers 32, 32', 32'', . . . All lateral wipers 32', 32'', . . . are arranged to swing about the fixed point 33. Only the rear wiper 32 has a straight wiping movement in the direction of the longitudinal axis of the shoe in order to prevent the formation of plaits at the end or in the middle of the heel of the shoe.

The front edge of the rear wiper 32 is shaped 50 as to abut in its nailing position against the edges 55

of the lateral wipers 32'. The movement of the pressure plungers and of the wipers pivoted thereto is limited by stops 34 screwed to the wipers and coming into contact with the leather band 35 which is suitably held in the machine to enclose the heel or the toe of the shoe.

Underneath the rear plunger 28 there is arranged a sliding valve 36 connected by the stem 37 to the knee-lever 38. This lever is pivoted on the fixed bolt 39 and is connected by the bar 40 to the treadle 41.

Fig. 2 shows the machine while it is running idle. The oil pressed through the duct 21 into the chamber 43 flows through the port 74, between the seats of the valve 36, the port 71, the room in front of the plunger 28, and the bore 73 into the return pipe 70.

By operating the treadle 41 the controlling valve 36 is moved into operative position shown in Fig. 1. The continuously running pump feeds pressure oil into the cylinder chambers 42, 43. The oil enters through the port 74 between the seats of the valve 36 and then through the port 68 into the chamber 29. The growing pressure in the chamber 29 acts upon the plungers 28, 28', 28''... only, as the way of the plunger 9 is limited by the sole pressure 23 and the way of the plunger 11 is limited by the fixed stop 22 against which the shoe end is abutting. By this pressure all plungers 28, 28',... and the wipers screwed and linked thereto move against the shoe. Thus the upstanding upper is wiped over the last. This overwiping takes place for all shoe forms in a perfectly uniform manner, as owing to the pressure in the common pressure chamber 29 always all plungers are moved at the same time and with the same force. Owing to the high uniform pressure exerted by all wipers the edge of the last is visibly marked on the upper leather so that a subsequent pounding up may be dispensed with. The degree of pressure of the oil is always the same in the raising ducts 20 and 21 and in the cylinder chambers 29, 42 and 43. The diameter of the plunger 11 is so proportioned relatively to the individual plungers 28, 28',... that the shoe cannot yield outwardly while being overwiped. The degree of pressure for heavy and light shoes can be regulated by the hand wheel 44. The excess of pressure oil which is continuously fed by the pump is returned against the action of the spring in the overflow valve through the overflow pipe 45 into the tank. It is obvious that a repeated overwiping can be obtained by repeatedly moving the controlling valve 36 to and fro.

To the knee lever 38 is pivoted a link 46 connected to the coupling lever 47. The coupling lever is arranged on the shaft 48 in the machine head. By operation of the treadle at first the controlling valve 36 is brought into effective position as already described and as shown in Fig. 1, and then a bolt coupling 75 is released by means of the arm 49 fastened to the lever 46. The movement of the coupling is derived from a belt-pulley on the shaft of the pump 16. The description of the bolt coupling is omitted as it is well known in the art. To the shaft 16 of the coupling is keyed a toothed wheel 51 which is in mesh with the toothed wheel 52 fixedly connected to the eccentric shaft 53. The diameter of the wheel 52 is twice as long as the diameter of the wheel 51. On the eccentric is arranged a strap 54 connected by the bolt 56 to the lever 55. The lever 55 is journaled in the machine head by the shaft 57 and is connected to the tack driving plate 59

by means of the link 58. The tack driving hammers 61 are fastened to the hammer bars 60 and drive the tacks for fastening the upper leather to the insole. The follower 62 attached to the tack driving plate 59 serves for carrying the hammer bars 60 back into the upper position. The rear end of the lever 55 is connected by the link 63 to the rack 64 guided in the post 65 of the tack-apparatus. The rack engages into a gear keyed on the bearing shaft of the tack-drum 66. By the movement of the lever 55 the drum is oscillated in order to separate the tacks. The means for separation of the tacks and the control of the number of the tacks are well known in the art and need not to be described in detail.

On the eccentric-shaft 53 is keyed a roller lever 67 about 45° in advance of the lowest position of the eccentric, see Fig. 2. This roller lever presses at the end of its rotation the coupling lever 47 down back into its end position, so that the coupling is freed from the arm 49. The controlling valve is thereby moved into the position of Fig. 2.

The oil in the high pressure room 29 flows now through the channel 68, the lateral discharge pipe 69 and the outlet pipe 70 back into the tank. On the other hand the oil fed by the continuously working pump presses the plungers 28, 28',... back until the step of the plunger 28 uncovers the channel 72 and the whole quantity of the fed oil returns through the channel 72, and the pipe 70 into the tank. The channel 73 is provided only for limiting the way of the plungers 28 in a forward direction, when no shoe is introduced and the control valve 36 is held in the operative position shown in Fig. 1. In this case the pressure fluid entering into the chamber 29 leaves the latter through the port 73 without any material effect upon the plungers. At the end of the operation the plunger 11 is pushed outward by the compressed spring A against a suitable stop. The port 71 leads to a semicircular room 71', and the port 68 leads to a semicircular room 68'. Thus a single port 72 is needed for all plungers 28 to 28'''. But this port must not be uncovered by the plunger 28 until all lateral plungers are returned into their rear position. This is obtained by the provision of the compression spring C behind the plunger 28 only. Thus at first all lateral plungers are moved to the rear and the plunger 28 is moved as last one into this position.

The shoe being lasted in one operation at the toe or at the heel is turned about the axis of the plunger 9 for 180° to be lasted at the heel or toe part of the shoe in a continued operation in the manner described.

As shown in Fig. 8, one or more plungers 28''''' can be removed from operation by pushing stop pins 74' into holes of the said plungers.

What I claim is:

1. In a shoe end lasting machine a series of wiping and nailing instrumentalities supported by a series of radially arranged plungers, a shoe support carried by a vertically movable plunger and connected to a horizontally movable plunger, a continuously running pump feeding a pressure fluid to the cylinders of the single plungers and back to a pressure fluid container and means for successively directing the constantly fed pressure fluid to one or the other side of the plungers to bring them into and out of their working position.

2. In a shoe end lasting machine a series of wiping and nailing instrumentalities supported by a series of radially arranged plungers, a shoe

- support carried by a vertically movable plunger and connected to a horizontally movable plunger, a continuously running pump feeding a pressure fluid to the cylinders of the single plungers and back to a pressure fluid container, means under the control of the attendant for directing the constantly fed pressure fluid to one side of the plungers so as to press them into operative position, and means acting automatically at the 5 end of the operation to direct the said fluid to the other side of the plungers and to bring them back into their initial position, and a relief valve within the duct connecting the pump to the plungers opening when the pressure of the fluid 10 exceeds a predetermined degree. 15
3. In a shoe-end lasting machine, a series of wiping and nailing instrumentalities, a series of radially arranged plungers connected to these instrumentalities, a continuously running pump 20 feeding a pressure fluid, common fluid chambers on both ends of the plungers, ducts leading the pressure fluid from the pump to the rear chamber situated on the free ends of the plungers, a relief valve within these ducts, ducts leading 25 the pressure fluid from the pump to the front chamber situated on the ends of the plungers connected to the instrumentalities, outlet ducts from the chambers, means under the control of the attendant for directing the fed fluid to the rear chamber, and means acting automatically at the 30 end of the operation to direct the said fluid to the front chamber. 35
4. In a shoe-end lasting machine, a series of wiping and nailing instrumentalities, a series of radially arranged plungers connected to these instrumentalities, a continuously running pump feeding a pressure fluid, common fluid chambers at each end of the plungers, ducts leading the pressure fluid from the pump to the rear chamber situated on the free ends of the plungers, a relief valve within these ducts, ducts leading the pressure fluid from the pump to the front chamber situated on the ends of the plungers connected to the instrumentalities, outlet ducts from 40 the chambers, a spring tending to keep one of 45
- the plungers in a position to interrupt the communication between the front chamber and the outlet ducts, means under the control of the attendant for directing the fed fluid to the rear chamber, and means acting automatically at the end of the operation to direct the said fluid to the front chamber. 5
5. In a shoe end lasting machine a last carrier, a vertically movable plunger supporting the carrier, a horizontally movable plunger connected to the carrier, means under the control of the attendant for moving the said plungers in succession by means of a pressure fluid fed to the plungers, and abutments limiting the movements of said plungers in bringing the last carrier to its lasting position. 10
6. In a shoe-end lasting machine, a last carrier rotatable about a vertical axis and movable into and out of lasting position, a plunger connected to the carrier, a continuously running pump feeding a pressure fluid, and means under the control of the attendant for moving the plunger by means of the fed pressure fluid into lasting position. 15
7. In a shoe-end lasting machine, means for wiping the upper-margin over the last, hydraulic means for moving the wiping means, means controlling the hydraulic means and operated by the attendant, power driven nailing devices for fastening the overwiped upper-margin, and automatic means acting in succession to the said hydraulic means to operate the nailing devices. 20
8. In a shoe end lasting machine a central wiper having a straight movement and a plurality of lateral wipers arranged side by side and guided laterally by the central wiper to get to their working position by swinging about a common fixed point situated in the longitudinal axis of the shoe. 25
9. In a shoe-end lasting machine, wipers, hydraulic plungers for moving the wipers, and means for immobilizing some of the wipers in their inoperative position. 30

WILHELM MÜLLER. 45
